Des. 189,542
Patented Jan. 3, 1961

189,542

CAKE SERVER

Abel E. Garner, 480 Park Ave., New York, N.Y.

Filed July 13, 1960, Ser. No. 61,349

Term of patent 14 years

(Cl. D44—19)

Fig. 1 is a perspective view of a cake server showing my new design;

Fig. 2 is a top plan view thereof on a reduced scale;

Fig. 3 is a bottom plan view thereof;

Fig. 4 is a front elevational view thereof; and

Fig. 5 is a side elevational view thereof.

The cover face opposite that shown is similarly ribbed.

I claim:

The ornamental design for a cake server, substantially as shown and described.
